UNITED STATES PATENT OFFICE.

OTTO BARTEL, OF NEW YORK, N. Y.

DESIGN FOR A CLOCK-DIAL.

SPECIFICATION forming part of Design No. 18,282, dated May 1, 1888.

Application filed March 21, 1888. Serial No. 268,016. Term of patent 3½ years.

To all whom it may concern:

Be it known that I, OTTO BARTEL, of New York city, New York, have invented and produced a new and original Design for a Clock-Dial, of which the following is a specification.

The accompanying illustration represents a face view of my newly-designed clock-dial.

The leading feature of this design consists of a graduated circle containing the representation of a water-mill.

a represents a graduated circle with the numerals from 1 to 12. Within this circle there is contained the representation of a wa-

ter-mill, *b*, having wheel *c*. The water-mill is represented as surrounded by a landscape that is fringed by a mountain range. A boy fishing in the stream is also represented.

What I claim is—

The design for a clock-dial, consisting of a circle containing the representation of a landscape, mountain range, brook, and water-mill, substantially as shown.

OTTO BARTEL.
